GEORGE KING, OF FREDERICK, MARYLAND.

Letters Patent No. 90,558, dated May 25, 1869.

IMPROVED SASH-LOCK.

The Schedule referred to in these Letters Patent and making part of the same.

To all whom it may concern:

Be it known that I, GEORGE KING, of Frederick, in the county of Frederick, and State of Maryland, have invented a new and useful Improvement in Sash-Locks; and I do hereby declare that the following is a full, clear, and exact description thereof.

The object of my invention is to produce a simple and convenient self-adjusting sash-lock.

To enable others skilled in the art to make and use my invention, I will proceed to describe its construction and operation, reference being had to the accompanying drawings, in which like letters indicate like parts, and in which—

Figure 1 represents an upright view of my invention.

Figure 2 represents a top view of the same, taken through the line *x*.

A A show the uprights of an ordinary sash-frame, on the inside of which, near the top of the frame, the screws *b' b'* are inserted, from which depend the perpendicular rods *c' c'*.

B is an ordinary sash, having its opposite sides grooved to receive the rods *c' c'*.

d' d' are bevel notches cut in the sash near the top on each side, in which play the metal catches *c' c'*, which are made flat, nearly the length of the notch, and have a circular hole drilled through the end of each, through which the perpendicular rods pass.

When it is desirable to raise the window, all that is necessary is to throw the sash up suddenly, so that when it falls back the catches are thrown out of a horizontal line and up against the top of the bevel-notches, which will cause the edges of the drilled holes in the end of the catches to bind against the rods, and the sash will thus be held securely in position by its own weight.

To lower the window, raise the sash slightly and let down gently.

I am aware that a metal dog, pivoted in and extending through the sash, is in use in the patent of W. H. Sible, and therefore do not claim this arrangement; but

What I do claim as new, and desire to secure by Letters Patent, is—

Loose metal dogs, working upon pendent rods, and resting on the bottom or square of the slot or mortise when the window is descending, as hereinbefore described and set forth.

The above specification of my improvement in sash-locks, signed this 10th day of March, 1869.

GEORGE KING.
